ART OF CRACKING HYDROCARBONS

Continuation of application Serial No. 24,734, filed April 21, 1925. This application filed July 12, 1929.
Serial No. 377,816.

This invention relates to improvements in pressure distillation processes for cracking heavier hydrocarbon oils, such as gas oil, for the production of lighter hydrocarbon oils, such as gasoline and pressure distillate, therefrom. This application is a continuation of a prior application filed April 21, 1925, Serial No. 24,734.

When hydrocarbon oils are distilled under pressure at a cracking temperature, they are broken up into lighter oils of less complex molecular structure. In addition to these lighter oils, the products of the cracking reaction also include carbon, or tar or pitch constituents, and fixed gases. In condensing the vapors in the pressure distillation, the fixed gases escaping from the pressure still with the vapors of the cracked oil tend to carry a certain proportion of the condensable components of the vapors with them through the condenser uncondensed. These uncondensed vapors thus associated with the fixed gases escaping uncondensed from the condenser include particularly the very light constituents which are desirable components of motor gasoline. If the condensing operation is carried out under pressure, the proportion of such vapors which are condensed may be increased, but, in this case, when the pressure on the condensed distillate is reduced to atmospheric pressure the very light constituents again escape as vapors from the condensed distillate. The proportion of such light constituents which escape from the condensed distillate when the pressure thereon is reduced to atmospheric pressure varies with the degree of pressure under which the condensing operation is conducted. However, this relationship is not a direct proportion as a much larger increment of these light constituents are condensed, and subsequently escape on reduction of pressure, as a result of the application of a relatively small initial increment of pressure above atmospheric during the condensing operation. In addition to the gas mixtures produced in pressure still operation, normal refinery operation is also accompanied by the production of other gas mixtures including condensable constituents suitable as components of gaso-

line or other commercial oils, such for example as the gas mixtures produced in coke still operation. Hitherto, it has been the practice to recover such condensable constituents from these various gas mixtures, if at all, by separate and additional operations such as those employed in the recovery of gasoline from natural gas and casing head gas. This invention includes improvements in the recovery of gasoline constituents from such gas mixtures, and especially from the gas mixtures produced in pressure distillation or other cracking processes; and includes particularly a cyclic method of operation eliminating such separate and additional operations as have previously been employed for the treatment of such gas mixtures. Likewise, a considerable proportion of the products of the cracking distillation is composed of unsaturated hydrocarbons, many of which are undesirable as components of gasoline and other commercial oils, because of unpleasant odor, instability, etc. Attempts have hitherto been made to saturate these undesirable unsaturated constituents by the addition of hydrogen thereto, such as by maintaining the vapors from the pressure still under pressure, or by mixing them with hydrogen or hydrogen containing gases, but without marked results. This invention also includes improvements in the operation of pressure stills whereby such undesirable unsaturated constituents are treated in the pressure still system to form saturated or more saturated compounds improving the quality of the pressure distillate. The invention further includes improved methods of operating pressure stills for controlling the pressure therein and for promoting the vaporization therein of constituents suitable as components of the desired pressure distillate. Other features and advantages of the invention will be apparent as the description proceeds.

According to the present invention, charging stock supplied to the pressure still is first employed as an absorbing medium for scrubbing the uncondensed vapors and gases from the pressure still, or other gas mixtures including condensable components suitable as components of the desired pressure distil-

late, and the absorbed constituents are then distilled from the charging stock as it is supplied to the pressure still system, and the absorbed condensable vapors distilled in the pressure still system are taken off and condensed with the vapors forming the pressure distillate. The gas mixture supplied to the scrubbing operation may be that produced in the same or other pressure stills, or the 10 gas mixture produced in other cracking operations, or other refinery gases including constituents suitable as components of the desired pressure distillate, or a mixture including various of these gases and gas mixtures. 15 The gas mixture supplied to the scrubbing operation advantageously includes all components which escape from the pressure distillate when the pressure is reduced to a substantially lower pressure than that maintained in the pressure distillation or to atmospheric pressure. The charging stock containing the absorbed constituents therein may be introduced into the charge of oil undergoing distillation in the pressure still, or it 20 may be supplied to the pressure still through a refluxing operation. One particularly advantageous way of carrying out the invention is to introduce the supply of fresh charging stock containing the constituents absorbed in the scrubbing operation into direct contact with the vapors from the pressure still in a reflux tower through which the pressure still vapors pass to the condenser. All or part of the charging stock containing 25 absorbed constituents may thus be introduced into a refluxing operation in accordance with the present invention, or part of the charging stock may be elsewhere introduced into the pressure still system. 30 The invention will be further described 40 more particularly in connection with the pressure distillation of gas oil character charging stocks for the production of gasoline, or gasoline containing pressure distillates, but it is intended and will be understood that this further more detailed description of one way of carrying out the invention is illustrative of the invention and that the invention is not limited thereto. Reference will be made, in connection with this 45 further description of the invention, to the accompanying drawings, which illustrate in a diagrammatic and conventional manner one type of apparatus adapted for carrying out 50 the process of the invention. The pressure still illustrated in the drawings is of the general construction and operation described in United States Letters Patent No. 1,285,200 granted to the Sinclair Refining Company 55 November 19, 1918 on the application of Edward W. Isom. The invention is applicable in connection with other pressure distillation systems, but this particular type of pressure still has been chosen for the purpose of illustration as representing a type of pressure

still, and of pressure still operation, to which the invention is applied with advantage.

In the accompanying drawings

Figs. 1 and 1A, taken together, represent in elevation and partly in section with parts broken away a pressure still system and associated apparatus adapted for carrying out the process of the invention,

Fig. 2 represents in elevation and partly in section a modified arrangement of the condenser and receiver together with a gas release tower, and

Fig. 3 is a flow sheet illustrating in diagram the process of the invention.

Referring to Figs. 1 and 1A of the drawings, the pressure still illustrated comprises a bulk supply tank 1 and a battery of heating tubes 2, the heating tubes being located in the heating flue of a furnace 3 and the bulk supply tank being arranged away from the furnace, and a circulating pump 4 and circulating connections 5, 6 and 7 connecting successively the bulk supply tank, the circulating pump, the lower end of the heating tubes, and the upper end of the heating tubes and the bulk supply tank. Arranged above the bulk supply tank is a reflux tower 8 having a plurality of baffles 9 therein. A vapor line 10 is arranged to conduct vapors from the vapor dome 11 on the bulk supply tank to the lower end of the reflux tower and a reflux return line 12 is arranged to conduct reflux, and admixed fresh oil, from the lower end of the reflux tower to the upper end of the circulating connection 5 on the suction side of the circulating pump 4. The reflux tower, 100 the bulk supply tank, and the circulating connections may with advantage be insulated against heat loss by the provision of suitable heat insulating jackets of material such as mineral wool thereon. A connection 13 is 105 provided for pumping out and charging the still and a tar draw-off connection 14 is arranged for use during the operation of the still.

Vapors escape from the upper end of the 110 reflux tower 8 through the vapor line 15 to a condenser 16. The condenser discharges through connection 17 into the receiver 18 which is provided with a distillate outlet 19 and a gas outlet 20. The gas outlet from the 115 receiver connects to a header 22 (the gas line being connected at D—D as shown). Gas mixtures from other pressure stills, or from other cracking operations, or other refinery gases containing condensable hydrocarbon 120 vapors, may be supplied through the header 21. From this point the gas mixture is conducted to the scrubbing tower through connection 22. The pressure in the pressure still may be controlled by the regulating 125 valve 23 arranged in the vapor line 15 between the reflux tower and the condenser, or the pressure may be reduced and regulated beyond the condenser or receiver. When the receiver is maintained under any 130

substantial pressure, it is advantageous to employ the arrangement of apparatus illustrated in Fig. 2. Where this arrangement of apparatus is employed, the vapor line 15 from the reflux tower is connected to a condenser 24 (the vapor line being connected at E—E as shown) and the gas connection 22 to the scrubbing tower is connected to the common connection 25 from the receiver 26 and the gas release tower 27 (at F—F as shown). In this modified arrangement of apparatus, the condenser 24 discharges into the receiver 26 which is provided with a gas release line 28 and a distillate discharge line 29. The line 29 connects to a header 30 into which the distillate from a number of pressure stills may be discharged. An auxiliary distillate discharge connection 31 is also provided for use as required. Here the pressure may be reduced and regulated by control valve 32, or the condenser may be operated under substantially the pressure prevailing in the still and the pressure reduced and regulated beyond the condenser, for example by control valve 33, or the receiver 26 may also be maintained under the pressure prevailing in the still. From the header 30 the condensed distillate is discharged through connection 34 into the gas release tower 27 where the pressure is reduced substantially to atmospheric. Excess gases and vapors absorbed in the distillate under the higher pressure in the receiver or condenser are then liberated and escape through connection 35 and the distillate free from such constituents is discharged through connection 36 under substantially atmospheric pressure. The released gases and vapors escaping from the receiver through connection 28 and escaping from the gas release tower through connection 35 pass together to the scrubbing tower through connection 25.

Again referring to Figs. 1 and 1A, the gas mixture from connection 22 is introduced into the lower end of the scrubbing tower 37 through connection 38 and passes upwardly therethrough over the baffles or other gas and liquid contact promoting means with which the scrubbing tower is provided. The stripped gases escape from the upper end of the scrubbing tower through connection 39 and are discharged into a gas holder 40 through connection 41. A valved by-pass connection 42 is also provided between gas line 22 and the gas line 41. Fresh oil is pumped from the charging stock tank 43 by means of pump 44 through connection 45 to the upper end of the scrubbing tower 37 through which it flows downwardly in countercurrent contact with the gases and vapors flowing upwardly therethrough. From the lower end of the scrubbing tower, the oil together with the constituents absorbed therein in the scrubbing tower is discharged into storage tank 46 through connection 47. A

header 48a may connect to this storage tank 46 from which a number of pressure stills may be supplied with fresh oil containing the constituents absorbed in the scrubbing tower. A pump 49 is provided for supplying fresh oil from this tank to the pressure still system illustrated in Fig. 1. From the pump 49 one feed oil line 50 leads to the bearings of the circulating pump (the feed line being connected at C—C as shown), and another feed oil line 51 leads to the upper end of the reflux tower 8 (this feed line being connected at B—B as shown). The feed line 51 connects to a spray head 52 arranged in the upper end of the reflux tower for spraying fresh oil downwardly therethrough in direct contact with the rising vapors from the pressure still. The flow of oil through the feed lines 50 and 51 may be controlled by valves 54 and 53 respectively. Fresh oil may also be supplied to other pressure stills through connection 48 by means of the same pump. The major proportion of fresh oil is supplied to the upper end of the reflux tower and the minor proportion is introduced through the bearings of the circulating pump. The supply of oil introduced into direct contact with the vapors in the reflux tower is regulated to control the refluxing operation therein, and additional oil required to maintain the still charge is supplied through the bearings of the circulating pump, a minimum sufficient to cool and protect the bearings of the circulating pump being at all times supplied thereto.

As an illustration of one way of carrying out the present invention for the production of gasoline from gas oil in the apparatus illustrated, the still is charged with 8,000 gals. of gas oil and brought to cracking conditions of temperature and pressure in the usual way. After being brought to operating conditions, the introduction of fresh oil into the reflux tower is begun and the vapors escaping from the reflux tower are condensed and the distillate discharged through the condenser to the receiver. With a gas oil character charging stock, pressures in the neighborhood of 90 to 125 lbs. per sq. in. may be employed; but the pressure employed may vary, for example, with lighter charging stocks such as kerosene character charging stocks pressures up to 300 lbs. per sq. in. or more may be used. This pressure may be maintained throughout the condenser and receiver but separation of the distillate and gases is advantageously effected at a substantially lower pressure than that maintained in the still, for example, separation of gases and distillate may to advantage be effected at atmospheric pressure or only sufficiently above atmospheric pressure to overcome the frictional resistance of the scrubbing tower and connections thereto to the flow of gases therethrough. Initially, fresh

oil is supplied at approximately the rate at which distillate is taken off, for example with a distillate rate of 1,000 gals. per hour fresh oil may be supplied at a rate of about 1,000 gals. per hour. Before the pitch content of the charge reaches saturation, the supply of fresh oil is increased and the withdrawal of tar laden oil from the still charge is begun, the rate of supply of fresh oil and of withdrawal of tar laden oil being regulated to maintain the pitch content of the charge below saturation. For example, with a distillate rate of 1,000 gals. per hour fresh oil may be supplied at a rate of about 2,500 gals. per hour and tar withdrawn at a rate of about 1,500 gals. per hour. Sufficient fresh oil is supplied to the upper end of the reflux tower to maintain the head temperature therein at the desired point for the production of the desired character distillate and the balance of the fresh oil is introduced into the circulating charge in the still. By providing a heat insulating jacket on the reflux tower, a large proportion of the fresh oil may be supplied through the reflux tower in direct contact with the vapors therein.

The charging stock supplied to the pressure still may, for example, be a gas oil having a gravity in the neighborhood of 28° to 35° Be. On its way to the pressure still, this charging stock is passed through the scrubbing tower in countercurrent to the hydrocarbon gas mixture rising therethrough. The relative supply of fresh oil and of gas mixture to the scrubbing operation will vary with the character of the fresh oil and with the amount of gases available, but in normal operation from 150 to 250 gals. of oil per thousand cubic feet of gas mixture will be employed. This ratio, however, may vary from somewhat less than 100 to more than 400 gals. per thousand cubic feet of gas mixture. The gas mixture supplied to the scrubbing operation may include the uncondensed vapors and gases produced in pressure stills in the refinery together with uncondensed vapors and gases from other cracking operations and other hydrocarbon refinery gas mixtures in varying proportions. Not only the amount, but also the character of the gases and gas mixtures available in the refinery may vary from time to time, for example both the composition and the amount of uncondensed vapors and gases may vary at different periods in the same pressure distillation operation. These variations tend to be offset by the relatively large amount of oil supplied to the scrubbing operation. In the scrubbing tower approximately 20% to 30% of the total gas mixture is absorbed in the oil. Normally, the supply of oil required for pressure still operation is so much in excess of that required for absorption that substantially all absorbable constituents of the

gas mixture are removed. With a gas mixture containing both saturated and unsaturated constituents, the gas oil charging stock selectively absorbs the unsaturated constituents, for example, from 60% to 75% of the available unsaturated constituents as compared to 15% to 20% or somewhat more of the available saturated constituents. Condensable constituents recovered as such from the gas mixture supplied to the scrubbing operation may amount to as much as 3 to 5 gals. per thousand cubic feet of gas mixture or more. These condensable constituents are liberated from the fresh charging stock in the pressure still system and are condensed and collected with the pressure distillate.

The gas mixture discharged from the pressure still, or pressure stills, either from the receiver or from the receiver and the gas release tower, includes both saturated and unsaturated hydrocarbons together with minor proportions of hydrogen, and sometimes carbon dioxide or carbon monoxide in very small amounts. As a typical analysis, the pressure still gas mixture may have a content of unsaturated hydrocarbons of about 31.7% and of saturated hydrocarbons of about 66.6% by volume; successive absorption in 70% H_2SO_4 , 80% H_2SO_4 and finally in fuming sulfuric acid removing the unsaturated constituents of this gas mixture successively to the extent of 3.9%, 13.5%, and 13.5%. Another refinery gas mixture which may be supplied to the scrubbing tower in carrying out the present invention is the mixture of uncondensed vapors and gases from coke still operation. As a typical analysis, such gas mixtures may have a content of about 32.2% of unsaturated hydrocarbons and about 65.7% of saturated hydrocarbons together with minor proportions of hydrogen, and sometimes very small amounts of carbon dioxide and carbon monoxide; 70% H_2SO_4 , 80% H_2SO_4 and fuming sulfuric acid removing successively about 4.8%, 12.2% and 15.4% of the gas mixture. As a typical analysis of the stripped gases escaping from the scrubbing tower, for example, when a mixture containing from 50 to 60% of pressure still gases together with coke still gases making up the balance of the foregoing typical analyses is passing through the scrubbing tower, the stripped gas mixture may have a content of unsaturated hydrocarbons of about 14.8% and of saturated hydrocarbons of about 82.3% 70% H_2SO_4 , 80% H_2SO_4 and fuming sulfuric acid removing successively 0.8%, 6.6% and 7.0%. The stripped gas is also substantially reduced in volume as compared to the volume of gas mixture supplied to the scrubbing operation.

The fresh oil charged with the constituents absorbed in the scrubbing tower is then supplied to the pressure still system, and is ad-

vantageously supplied to the upper end of the reflux tower in direct contact with the vapors therein, as illustrated in the drawings and as previously described. As the oil flows downwardly through the rising vapors of the cracked oil, it is heated by heat given up by the vapors and cools the vapors. The heavier constituents of the vapors are thus refluxed to the still. At the same time, the absorbed constituents are liberated in a gradual and progressive manner as the oil flows downwardly through the reflux tower. The absorbed condensable and non-reacting constituents are thus vaporized and escape and are condensed with the pressure distillate. The absorbed unsaturated constituents tend to combine with the unsaturated constituents of the vapors forming the pressure distillate, and particularly with the less stable and more unsaturated hydrocarbons, forming more stable and more saturated hydrocarbons. The unsaturated constituents supplied to the pressure still system absorbed in the fresh charging stock may be in part condensable and in part incondensable under conditions of practical operation, and part of these constituents may be condensed as such or part of them may combine with unsaturated constituents of the vapors and gases in the pressure still system, which in turn might be condensable or incondensable under conditions of practical operation, to form constituents which are condensed and taken off with the pressure distillate. The unsaturated hydrocarbons absorbed in the fresh oil and supplied to the pressure still system therein do not again appear, but there is an actual decrease in the content of unsaturated hydrocarbons and an increase in the content of saturated hydrocarbons of the final stripped gas mixture released from the scrubbing operation. This is illustrated by the typical analyses given above.

In the operation of a battery of pressure stills in accordance with the present invention in which the gas mixture from the pressure stills and the gas mixture from the coke stills in the refinery were scrubbed in the fresh oil supplied to the pressure stills, the following average results were obtained over a 42 day period.

55 Gas mixture from pressure stills per day
Cubic feet 1,696,600
Pounds 120,100

Gas mixture from pressure stills per barrel charged
Cubic feet 123.8
Pounds 8.8

Gas mixture from coke stills per day
Cubic feet 1,187,000
Pounds 87,600

Gas mixture from coke stills per barrel charged	74.1	5.46	70
Cubic feet			
Pounds			
Total gas mixture per day	2,883,600		
Cubic feet			
Pounds	207,700		
Total stripped gas from absorber per day	2,345,500	75	
Cubic feet			
Pounds	143,000		
Total gas mixture constituents absorbed per day	538,100	80	
Cubic feet			
Pounds	64,700		

One of the important advantages of the present invention is that it combines with the pressure still operation the recovery of condensable hydrocarbons from the various hydrocarbon gas mixtures available in the refinery, such as the gas mixtures produced in the pressure still itself or in other refinery operations. With the exception of the scrubbing operation and the apparatus therefore, additional and separate apparatus and operations are eliminated, and the scrubbing operation in the combined system is greatly simplified. With reference to the scrubbing operation of the present invention, the pressure still charging stock is a good absorbing medium and because of the relatively large flow of oil through the scrubbing tower as compared to the flow of gas no particular care and regulation of the relative flow of gas and oil are necessary. Moreover, gas production in a given still corresponds roughly to the rate of distillation so that with high rates of distillation more fresh oil is required compensating for increased gas production. The relatively large quantity of fresh oil supplied to the pressure stills also avoids any necessity for a multiplicity of scrubbing towers or recirculation of the absorbing medium. As compared to separate oil absorption recovery systems, special still and handling equipment to recover the absorbed condensable hydrocarbons from the absorbing medium is eliminated, as is the operation of such apparatus, and there is no necessity for providing special absorbing mediums of high initial boiling point to avoid contamination of the recovered light oils. Moreover, as the recovered light oils are vaporized in the pressure still system and condensed with the pressure distillate, the provision of separate storage means is not necessary; and, as the recovered light oils may be refined with the pressure distillate, special refining operations carried out upon the gas mixture before it is subjected to absorption treatment, hitherto employed to avoid the high evaporation losses incident to the refining of the very light oils as recovered in separate operations, may also be eliminated. As illustrated in a diagrammatic manner in 130

the flow sheet constituting Fig. 3 of the drawings accompanying this application, in carrying out the present invention for the production of gasoline, to which the present invention is particularly applicable, gasoline constituents suitable as components of the desired pressure distillate are scrubbed from the gas mixtures in which they occur and absorbed in fresh charging stock, and the absorbed gasoline constituents are distilled from the fresh oil as it is supplied to the pressure still system and are taken off and condensed with the cracked vapors produced in the still. Another important advantage of the present invention is the improvement in the quality of the pressure distillates produced in pressure distillation processes which it makes possible. As has been pointed out above, the charging stock to the pressure still absorbs a large amount of unsaturated constituents from the gas mixture supplied to the scrubbing operation. The heavier more condensable constituents of the gas mixture, for example, may be predominantly unsaturated in character so that saturated constituents are concentrated in the unabsorbed gases. As the fresh oil is heated in the pressure still system, these absorbed unsaturated constituents are liberated within the pressure still system where they tend to combine with unsaturated constituents of the vapors forming the pressure distillate, and particularly with the less stable and more objectionable unsaturated hydrocarbons, forming more stable and more saturated hydrocarbons. In this aspect of the invention, it is particularly advantageous to supply to the scrubbing operation gas mixtures containing a considerable proportion of unsaturated components, such as the gas mixture produced in pressure distillation processes or in other cracking processes.

The present invention has several further additional advantages when carried out in connection with pressure distillation processes in which the vapors are subjected to a refluxing operation and when the fresh oil containing absorbed constituents recovered in the scrubbing operation is supplied to the refluxing operation in direct contact with the vapors therein. By carrying out the operation in this way, absorbed condensable constituents, such as uncondensed gasoline constituents, are liberated from the fresh oil in the refluxing operation by the heat given up by the vapors and these vaporized constituents pass off from the refluxing operation together with the vapors of the cracked oil without being subjected to the higher temperature prevailing in the pressure still proper. Likewise, in such operations, absorbed unsaturated constituents are progressively liberated from the fresh oil as it is heated up by contact with the vapors in the refluxing operation and are thus intermingled with the vapors of the cracked oil in a particular-

ly advantageous way and at a temperature which apparently promotes the combination of the various unsaturated components of the vapors and gases. The absorbed unsaturated constituents are thus also intermingled with the vapors from the pressure still proper without being subjected to the higher temperature prevailing in the pressure still proper. The introduction of light absorbed constituents into the fresh oil supplied to the refluxing operation also assists in promoting the refluxing operation, the vaporization and liberation of the absorbed constituents from the fresh oil assisting in cooling the vapors therein. 70 75 80

Another advantage of the present invention is that it provides an improved method of controlling the pressure in the pressure still operation. In addition to the condensable constituents and the reacting unsaturated constituents which are absorbed in the fresh oil supplied to the pressure distillation in accordance with the present invention, a certain amount of saturated fixed gases are absorbed as well as a certain amount of unsaturated fixed gases which may not react, and these latter gases are liberated from the charged fresh oil as it is supplied to the pressure still system, assisting in maintaining the pressure therein and providing a readily controlled partial pressure of fixed gases in the pressure still by reason of which vaporization of the desired lighter condensable constituents takes place therein at lower temperature than if the condensable constituents driven off alone were relied on to maintain this pressure. When the charged fresh oil is supplied through a refluxing operation, the absorbed fixed gases introduced with the fresh oil are quietly and progressively released in the refluxing operation without disturbing the oil in the pressure still proper and there is no tendency for the liberated gases in escaping to entrain heavier oil constituents as in the case where fixed gases are introduced beneath the surface of the liquid charge in a pressure still. In this way, the pressure still may be continuously kept charged with a fresh supply of fixed gases sufficient to maintain the desired pressure on the system. 90 95 100 105 110 115

I claim:

1. In the pressure distillation of heavier hydrocarbon oils for the production of lighter hydrocarbon oils, subjecting the heavier oil to a cracking temperature and taking off under pressure the gas and vapor mixture generated thereby, subjecting the gas and vapor mixture to a condensing operation, separating condensed distillate from the remaining uncondensed vapors and gases at substantially atmospheric pressure, scrubbing uncondensed vapors and gases from the separating operation with fresh heavier oil and introducing the heavier oil containing the con- 120 125 130

- stituents absorbed from the vapors and gases therein directly into the hot gas and vapor mixture generated in the cracking operation, separately discharging unabsorbed gases
5 from the scrubbing operation, and taking off together absorbed constituents liberated from the fresh heavier oil and the vapors of the cracked oil without again subjecting them to the cracking temperature.
- 10 2. In the pressure distillation of heavier hydrocarbon oils for the production of lighter hydrocarbon oils, subjecting the heavier oil to a cracking temperature and taking off under pressure the gas and vapor mixture
15 generated thereby, subjecting the gas and vapor mixture to a condensing operation, separating condensed distillate from the remaining uncondensed vapors and gases at substantially atmospheric pressure, scrubbing
20 uncondensed vapors and gases from the separating operation with fresh heavier oil and introducing the heavier oil containing the constituents absorbed from the vapors and gases therein to the cracking operation,
25 and discharging unabsorbed gases from the scrubbing operation.

In testimony whereof I affix my signature.
EUGENE C. HERTHEL.
